CLOTHES HANGER

Filed Nov. 6, 1926

Inventor
Robert West
By his Attorney
Warren E. Willis.

UNITED STATES PATENT OFFICE.

ROBERT WEST, OF NEW YORK, N. Y., ASSIGNOR OF ONE-HALF TO HARRY W. MARSHALL, OF BELLVILLE, NEW JERSEY.

CLOTHES HANGER.

Application filed November 6, 1926. Serial No. 146,641.

This invention relates to supports with particular reference to such devices as are used to receive clothes hangers.

One of the objects of this invention is to provide a hanger support capable of accommodating a plurality of adjustable hangers simultaneously.

A further aim is in the provision of means whereby clothes suspended from the device will be free from contact with the adjacent wall avoiding collection of dirt.

A still further characteristic is to provide a display support for clothing stores that utilizes little space and may be conveniently carried in a traveller's suit case or the like.

These and other objects, such as durability, low cost of manufacture, etc., are accomplished by the novel construction, combination and arrangement of parts, hereinafter described and illustrated in the accompanying drawing, forming a material part of this disclosure, and in which:—

The figure is a perspective view of the preferred form of the invention showing the application thereto, of a conventional clothes hanger.

Referring now in detail to the drawing, the numeral 10 generally designates a wall or partition.

30 The bracket or support consists of a diagonal rod 11 having an eye 12 at its upper end connecting laterally with an adjacent eye 13, to receive nails or any preferred attaching means such as the tacks or push pins 35 14 entered into the wall 10.

Continuing downward from the eye 13 is a vertical strand 15 intercoiled and connected by twists 16 to an element 17 formed on an eye 18 also receiving a nail or the like. Obviously the ends of the wire may be joined by other equivalent means, such as butt welding or otherwise as may be preferred.

40 Leading outwardly from the eye 18, perpendicular to the wall 10 is a horizontal mem-

ber 19 connecting with the diagonal bar 11, 45 at 20 the member 19 being undulated to provide a plurality of down reaching loops 21 adapted to receive the wire hook 22 of a conventional clothes hanger 23.

Thus it may be seen that the support is of 50 unitary construction and is capable of accommodating a plurality of hangers; also it is portable and is quickly and easily mounted in operative position. Furthermore it takes up very little room and has the added advantage 55 of keeping the clothes from contacting the adjacent wall, thus avoiding collection of dirt.

It will be apparent that, due to the shape and moderate weight of the support, it may be easily carried by travellers within their 60 baggage and put up by use of the push pins shown, thus being readily portable.

Although I have described the preferred form of my invention, it is to be understood that the foregoing is not to be interpreted as 65 limitative, as obviously changes in size, proportion, etc. may be made without departing from the spirit or scope of the claim hereto appended.

Having thus described my invention, what 70 I claim as new and desire to secure by Letters Patent, is:—

A clothes hanger holder comprising a wire bracket having a pair of circular eyes at its upper end, a single circular eye at its lower 75 end, a horizontal element extending outwardly from the lower eye, said element having inverted loops to receive a plurality of objects spaced from each other, and a brace reaching from the end of said element to the 80 connection between said upper eyes, all of said parts being made from a single strand of wire having its ends connected by twisting between the upper and lower eyes.

Signed at New York, in the county of New 85 York and State of New York, this 23rd day of October, A. D. 1926.

ROBERT WEST.
